ENDLESS TREAD BELT LINK

Thomas A. Snyder, Milwaukee, Wis.

Application August 11, 1928. Serial No. 299,071

7 Claims. (Cl. 305—10)

This invention relates to endless tread-belt links, and in particular to such links as used on very heavy mobile machinery such as power excavators. It is an improvement over the links disclosed and claimed in the patent of February 23, 1926, No. 1,574,042, to Bager and Lehman, and over the links disclosed and claimed in the patent of May 20, 1930, No. 1,759,049, to Mitchell L. Fykse.

10 Its principal object is to provide links that can be cast with a minimum of cores, thereby greatly reducing the cost of manufacture.

A further object is to eliminate foundry shrinkage strains, by so contriving my link that there are no parts which, owing to excessive thickness, would cool very slowly.

15 A still further object is to provide a link in which the objects stated above are attained without the sacrifice of strength or any other desirable quality.

20 A still further object is to provide novel means for the extrusion of dirt from the wheel-engaging surface of my tread link, for strengthening the links, and for securing the links together.

25 A still further object is to provide a novel abutment for the hinge-pins which connect the links. This abutment, by its shape, and by the fact that it does not serve as a strengthening member, may be chipped to accommodate interchangeable hinge-pins of uniform length, this chipping being effected with the minimum amount of labor and without the possibility of weakening the link.

30 Other objects and advantages will be evident to anyone skilled in the art, and therefore need not be herein more specifically set forth.

The invention consists in the novel parts and in the combinations and arrangements defined in the appended claims, and of which one embodiment is exemplified in the accompanying drawings, which are hereinafter particularly described and explained.

35 Throughout, the same reference number is applied to the same or to similar members. The sections are in all cases as viewed in the direction of the arrows.

Figure 1 is a plan view of the link, as seen from above.

Figure 2 is an elevation, being a view of Figure 1 as seen from the bottom of the sheet.

40 Figure 3 is a sectional elevation, taken as indicated in Figure 1 by the characters 3—3.

Figure 4 is a section through the wheel-engaging surface, taken along the line 4—4 of Figure 1.

45 Figure 5 is a section taken along the line 5—5 of Figure 1.

Figure 6 is a section taken along the line 6—6 of Figure 1.

Figure 7 is a plan view of one of the hinge-pins.

Figure 8 is an elevation of one of the T-pins.

Figures 7 and 8 are drawn to double the scale 60 of the other figures.

Figure 9 is a side elevation of a tread chain of my links, assembled with relation to the cooperating elements, part of the chain being in section.

Links of the same general sort as mine are 65 characterized by a broad ground-engaging surface 9, and spaced above it a single narrow wheel-engaging surface 10.

The wheels 30, 31, 32 and 33 are confined between upstanding flanges 11, and lugs 34 project 70 from the sides of the rim of the driving-wheel 33 engage against the faces 12 of the flanges 11. These flanges, instead of being continuous, as in the prior art, are made open at 13 to permit the extrusion of dirt from the runway 10, as the 75 wheels pass over it.

Each link is joined to the next by means of ears 14, which fit into recesses 15. Hinge-pins 16, each pass through a hole 17 in one wall of the recess 15, a hole 18 in the ear, and a hole 19 in 80 the other wall of the recess 15, and stop against an abutment 20. The hinge-pin is held in place by the head 21, of a T-pin 22, the shank of which passes through a hole 23 in one of the stiffening ribs 24, and is in turn held by a cotter-pin 25. 85

It will be noted that each of the hinge-pins 16 abuts against the edge of the abutment 20, rather than against the side face of a web. The importance of this lies in two facts. In the first place, it renders the space which contains the abutment 90 easier to empty of dirt than if this space were divided by a web extending across it. In the second place, irregularities in casting may be more easily chipped away from the edge of an abutment than from the side face of a web, in order 95 to accommodate each link to fit a uniform length of hinge-pin.

The strains from ear 14 to recess 15 of the same link are conveyed by two diverging ribs 26 and 27, which also serve as stiffening ribs. Other 100 stiffening ribs and stiffening upturned edges are provided, as clearly shown in the figures, and therefore need not be specifically referred to by number.

The sides of all ribs, and of the flanges 11 and 105 abutments 20, are sloped downward and outward from their summits; this being a very important feature.

Under the runway 10 there is a raised pocket 28 in the under surface of the link. The presence 110

of this pocket prevents an undue thickness at this point, with the disadvantages already enumerated. The arched shape of the pocket provides adequate support for the runway. In running, this pocket quickly fills with dirt and thus does not reduce the bearing surface of the link upon the ground.

5 Recesses 29 on the under surface of the link, indicate the proper points to bore through for the attachment of cleats for use on slippery ground.

10 Having now particularly described and illustrated one exemplification of my invention, I wish to be understood as not thereby limiting myself to the particular form shown, except in so far as 15 such limitations are specified in the accompanying claims.

I claim:

1. A cast-metal tread-belt-link for creeping traction, having: a broad ground-engaging portion; a centrally-located wheel-runway, spaced above, and formed by a domed portion upwardly extending from, the ground-engaging portion; and upstanding wheel-guiding flanges, formed integrally with, and supported by, the domed portion.

2. A cast-metal tread-belt-link for creeping traction, having: a broad ground-engaging portion; a centrally-located wheel-runway, spaced above, and formed by a domed portion upwardly extending from, the ground-engaging portion; and upstanding wheel-guiding flanges, formed integrally with, and supported by, the domed portion and the ground-engaging portion.

3. A cast-metal tread-belt-link for creeping traction, having: a broad ground-engaging portion; a centrally-located wheel-runway, spaced above, and formed by a domed portion upwardly extending from, the ground-engaging portion; stiffening ribs upstanding from the ground-engaging portion and bracing the runway; and upstanding wheel-guiding flanges, formed integrally with, and supported by, the domed portion, the ground-engaging portion, and certain of the stiffening ribs.

45

4. A cast-metal tread-belt-link for creeping traction, having: a broad ground-engaging portion; a centrally-located wheel-runway, spaced above, and formed by a domed portion upwardly extending from, the ground-engaging portion; and four upstanding wheel-guiding tapered projections, formed integrally with, and supported by, the domed portion; two of such projections being on each side of the runway.

5. A cast-metal tread-belt-link for creeping traction, having: a broad ground-engaging portion; a centrally-located wheel-runway, spaced above, and formed by a domed portion upwardly extending from, the ground-engaging portion; and four upstanding wheel-guiding tapered projections, two thereof being on each side of the runway, and each being formed integrally with and supported by, the domed portion and the ground-engaging portion.

6. A cast-metal tread-belt-link for creeping traction, having: a broad ground-engaging portion; a centrally-located wheel-runway, spaced above, and formed by a domed portion upwardly extending from, the ground-engaging portion; stiffening ribs upstanding from the ground-engaging portion and bracing the runway; and four upstanding wheel-guiding tapered projections, two thereof being on each side of the runway, and each being formed integrally with and supported by, the domed portion, the ground-engaging portion and certain of the stiffening ribs.

7. An integral cast-metal tread-belt-link for creeping traction, having: a broad ground-engaging portion; a single centrally-located wheel-runway, spaced above the ground-engaging portion; and four upstanding heavy tapered driving and wheel-guiding projections, two on each side of the runway, the driving-surface of each such projection being on that face thereof which is furthest from the other projection on the same side of the runway.
